US0D1105180S

(12) **United States Design Patent** (10) **Patent No.:** **US D1,105,180 S**
(45) **Date of Patent:** **** Dec. 9, 2025**

(54) **ICE TRAY**

(71) Applicant: **YETI Coolers, LLC**, Austin, TX (US)

(72) Inventors: **Dustin R. Bullock**, Austin, TX (US);
William Drinkwater, Austin, TX (US)

(73) Assignee: **YETI Coolers, LLC**, Austin, TX (US)

(**) Term: **15 Years**

(21) Appl. No.: **30/002,187**

(22) Filed: **May 2, 2025**

Related U.S. Application Data

(63) Continuation of application No. 29/904,455, filed on Oct. 6, 2023, now Pat. No. Des. 1,077,871.
